WINDOW GLASS CHANNEL

David C. Bailey, Amesbury, Mass.

Application July 11, 1930, Serial No. 467,184

9 Claims. (Cl. 296—44.5)

This invention relates to that class of window glass guides which are formed of metal bent in channel, or U-form and are generally employed in closed body automobiles.

5 The metal channels employed in the less expensive grades of automobiles are usually formed of steel or other comparatively low cost metal, but in those grades in which the best, or most expensive materials are demanded these metal channels are usually formed of non-corrodible metal, which is much more expensive than that which is more commonly used, as for example, stainless steel, silver, or chromium plated stock, so that the exposed portions of the channel will 10 constantly have an attractive appearance. As these metal channels are almost invariably secured in a groove within the window casing, only the edges of the sides thereof are visible, so that no advantage is derived from having the unexposed portion of the channel formed of expensive material.

The primary object of my invention is to provide a form of metal window glass channel which will, when installed, have all the advantages of 25 such a device when constructed from the more expensive non-corrodible metals, but which may be produced at an expense which will be but slightly greater than that of the less expensive construction more generally employed.

30 I accomplish this and other objects of my invention by providing the side edges of an ordinary metal channel with a finishing bead or molding of a more expensive or non-corrodible metal, so that its outward appearance will be the same as if the channel were constructed completely of the latter metal, and by providing 35 means whereby the finishing bead of the higher grade metal may be securely attached to the side edges of the channel formed of metal of the lower grade.

40 For a more complete disclosure of the invention reference is made to the following specification, in connection with the accompanying drawing, in which:—

45 Fig. 1 is a cross sectional view, on an enlarged scale of a preferred form of the invention.

Fig. 2 is a plan view, partly broken away, of one edge portion of the channel.

50 Fig. 3 is a longitudinal sectional view at line 3—3 of Fig. 1.

Fig. 4 is a detail view of a section of the finishing bead.

55 Fig. 5 is a detail perspective view showing a preliminary stage in the manufacturing operation of one form of the invention.

Figs. 6 to 11 inclusive are enlarged detail sectional views illustrating various modified forms of the invention.

Fig. 12 is a detail perspective view of a fragment of the construction shown in Fig. 11.

As shown in the drawing, a main channel portion *a* of common U-form is provided, which is formed from thin, comparatively inexpensive metal, and according to the invention, as shown in Figs. 1, 2 and 3, a series of slits *a'* are cut in 65 the edge portion of each side at suitable intervals, as shown in Fig. 5, said slits being extended inward from the edges for a sufficient portion of the height, or width of the sides, thus separating each edge portion into a series of tongues *a''*. As 70 shown in Figs. 2 and 3, alternate tongues of a series are bent inwardly of the channel and the others of the series are bent outwardly in opposite relation to the plane of the side from which they are formed.

The extent to which these tongues are bent from the plane of the side and the particular form into which they are bent may be varied indefinitely. As shown in Fig. 1 the tongues are rolled outward and inward into an approximately 80 semi-cylindrical formation, so that the adjacent tongues together form a transversely enlarged, or thickened, approximately cylindrical edge, which is divided by the plane of the side. A bead, or small molding *b* is provided which consists of 85 a strip of metal bent into partly tubular, or U-form, the metal of which it is constructed having an ornamental finish which is preferably rust proof, or proof against discolorations, so that it will always present an ornamental appearance. 90 The formation of the bead *b* may be somewhat varied, but in all instances is similar to the construction shown in Fig. 4, and is adapted to be placed over the transversely enlarged edge portion of each side of the channel by passing the 95 edge portion through the slot formed between the edges of the strip forming the bead and forcing the edges into clamping engagement with the inner and outer surfaces of the side, or the enlarged edge portion thereof, to which it is attached.

100 As shown in Fig. 1, the head *b* is formed cylindrically, so that its inner surface corresponds to the outer surface of the approximately cylindrical enlargement of the sides. If the bead is 105 of non-resilient metal it may be placed in position on the enlarged edge portion and clamped together against the sides thereof. If it is formed of somewhat resilient metal, it may be sprung open sufficiently to permit it to be placed in po- 110

sition and spring into clamping engagement. The bead may also be mounted on the edge by a telescoping operation, but as these channels are usually made in long strips, and a subsequent 5 clamping operation would be necessary, such a method is considered impractical.

As shown in Fig. 1, the rolled over tongues a^2 may also be employed for the purpose of holding a covering c for a cushioning lining e , by clamping the covering between the edge of the tongues 10 and the inner side of the channel. Also the outwardly bent tongues may be employed to hold felt strips d in position between the outer sides 15 of the channel and the sides of the casing groove in which it is located, the felt strips being, if it is desired, also adhesively connected to the sides of the channel grooves.

In the form of the invention shown in Fig. 6, the alternate tongues a^3 are shown as bent inwardly towards the base of the channel at the 20 outer and inner sides of the channel side and extended in divergent relation. Said tongues are also held in clamping engagement with the covering c' and felt strip d' and the bead b' is designed to be pressed on over the enlargement 25 formed by the tongues and to be resiliently engaged therewith, and also with the covering felt strip.

In the form of Fig. 7 the alternate tongues a^4 are shown as bent oppositely at right angles to 30 the sides and then outwardly from the channel bottom and convergently in curved formation, to provide a seat for the bead b^2 , which is similar to the form previously described and, when in position has its edge portions clamped against the inner portions of the tongues. The edges of the 35 bead are also engaged with the lining covering c^2 and felt strip d^2 , as in Fig. 6.

In Fig. 9 the alternate tongues a^5 are shown as bent oppositely at right angles to the sides, to 40 form the enlarged edge, and, in this instance, a lining covering c^3 is shown as extended over the top of the edge and downward on the outer surface of the side and as clamped between the opposite portions of the bead b^3 , which is shown in 45 this instance, as having its outer side portion extended for a distance down on the outer side of the channel, to give a finish to the side, and as turned out from the side, at the inner side, to prevent cutting the covering.

In Fig. 10, the construction shown is similar 50 to that of Fig. 9, except that only the alternate tongues a^6 are bent out of the plane of the sides, said tongues being bent inwardly of the channel at approximately right angles, and the other 55 tongues being left in the plane of the side. In this instance the form of the bead b^4 will be correspondingly changed, but will be similar to that of Fig. 9.

In the constructions of Figs. 8 and 11, instead 60 of slitting the edge portions of the sides to form tongues, from which the transversely enlarged edge-portion is to be formed, a series of tongues a^7 in Fig. 8, and a^8 in Fig. 11, are struck out from 65 the sides and bent inwardly of the channel, by cutting a series of longitudinal slits in each side and transverse slits therein which extend from the ends of the longitudinal slits, towards the edge, but terminate at a distance therefrom, thereby forming a series of apertures f in the 70 sides, as shown in Fig. 12. The constructions of Figs. 8 and 11 are practically the same, except that in Fig. 8 the edge portion of the side is left in the plane of the side and the tongue is extended towards the channel bottom at a slight

curvature and in Fig. 11 the edge portion is bent outward from the channel and the tongue is curved outward from the bottom. The beads b^5 and b^6 are also formed somewhat differently to conform to the edge and tongue portions with which they are engaged, but the construction and method of application is substantially the same as previously described. In this instance also the channel is lined with a felt cushion e' , e^2 , which is held in the channel by the tongues and protrudes through the apertures f , so that the felt is engaged with the sides of the casing groove in which the channel is located.

In all of the constructions above described the bead or molding having a finished surface which gives the channel an ornamental appearance is securely attached.

It will be understood that it is immaterial to the invention, so far as the matter of the generic means employed for securing the bead in position is concerned, whether the engagement of the edge portions of the bead with the sides is direct or through intervening material which it is desired to secure in position in or on the side of the channel.

I claim:

1. A window glass guide comprising a U-form metal channel having a series of transverse slits in the edge portion of each of its sides, to form tongues, said tongues being bent into transverse relation with the side in which they are formed, and a U-form metal bead mounted on each side and enclosing the tongues thereof with its edge portions clamped thereto at the inner sides of the tongues.

2. A window glass guide comprising a U-form metal channel having each of its sides cut inwardly from its edge to form a series of tongues, the alternate tongues of each series being bent inwardly therefrom and extended towards the opposite side, and a U-form metal bead mounted on each side and enclosing the tongues thereof, with its edge portions held in clamping engagement with the portions of the side therebetween.

3. A window glass guide comprising a U-form metal channel having the edge portions of each of its sides cut inwardly from the edge to form a series of tongues, a portion of which are bent inwardly of the channel, and a U-form metal bead enclosing the tongues of each side and having its edge portions extended towards the side and respectively engaged with the inner and outer surfaces of the side at the base ends of the tongues, to retain the bead rigidly in position thereon.

4. A window glass guide comprising a U-form metal channel having a regular series of slits in the edge portions of each of its sides, to form said portions into a series of tongues, the alternate tongues being bent in angular relation to the side from which they are formed, and a U-form metal bead enclosing said tongues and retained thereby in position to provide an ornamental finish for the edges of the sides of the channel.

5. A window glass guide comprising a U-form metal channel having the edge portions of each of its sides cut inwardly to an approximately uniform depth from the edge, to form a series of tongues, and having alternate tongues bent oppositely in angular relation to the adjacent portion of the side, and a U-form metal bead enclosing the tongues of each side and having its edges held in clamping engagement with the side at the inner side of the tongues.

6. A window glass guide comprising a U-form metal channel cut inwardly from the edge por-

- tions of its sides to form tongues, said tongues being bent inwardly of the channel and said channel having a lining with which said tongues are engaged to hold the lining in position, and a 5 U-form metal bead mounted on each side of the channel in position to enclose the edge portions thereof, said edge portions and tongues being clamped between the sides of the bead to hold the bead in position thereon. 80
- 10 7. A window glass guide comprising a U-form metal channel having a series of longitudinal slits formed in the edge portions of the sides thereof, and a series of transverse slits extending towards the edge of the sides from the ends of said longitudinal slits to form tongues therefrom, said tongues being bent to extend into the channel and providing openings in the sides thereof, and a lining in said channel engaged with the inner sides of said tongues and protruding through said 15 apertures. 85
- 15 8. A window glass guide comprising a U-form metal channel, having the edge portion of one 90
- 20 9. A window glass guide comprising a U-form metal channel, having the edge portion of one of its sides bent transversely to project inwardly and outwardly with relation to the plane thereof, to provide a transversely enlarged edge portion, a lining for the channel extending to said edge portion, and a U-form metal bead enclosing said edge portion and engaged with the lining and with opposite portions of the side to retain the lining in position on the channel surface and the bead in position on the side. 95
